SUPPLEMENTARY AUXILIARY APPARATUS
FOR PRIME MOVERSFrederick L. Dornbrook, Milwaukee, Wis., assignor
to Wisconsin Electric Power Company, Milwaukee, Wis., a corporation of Wisconsin

Application February 6, 1942, Serial No. 429,762

3 Claims. (Cl. 103—11)

Steam turbines are usually provided with oil pumps for the hydraulic operation of their governors and lubrication of their bearings. Emergency oil pumps are also provided for furnishing the pressure fluid for governor operation and bearing lubrication in case the regular oil pumps fail. Various means have been provided for driving the emergency oil pumps, but these have not always been foolproof, particularly where the emergency oil pumps are steam turbine driven. The object of the present invention is to provide a new and improved arrangement for the control of the emergency oil pumps and their drive in case the regular oil pumps fail.

The invention further consists in the several features hereinafter set forth and more particularly defined by claims at the conclusion hereof.

In the drawings:

Fig. 1 is a diagrammatic view of apparatus embodying the invention;

Fig. 2 is a sectional view taken on the broken line 2—2 of Fig. 3;

Fig. 3 is a sectional view, parts being shown in central vertical section while one of the parts is taken on the section line 3—3 of Fig. 2.

In the drawings, the numeral 5 designates the steam turbine and 7 and 8 the oil pumps for the hydraulic operation of its governor and lubrication of its bearings, respectively, these pumps usually delivering at different hydraulic pressures and being driven direct by the turbine as through a worm gear 9 or other suitable form of drive connection therewith. The hydraulic fluid for operating the governor 10 is supplied to the pump 7 from a suitable source of supply through a pipe 11 and delivered to the governor through a pipe 12. The lubricant for the turbine is supplied to the pump 8 by a supply pipe 13 and delivered to the bearings 14 of the turbine through piping 15.

In case either of the regular oil pumps fail, provision is usually made for cutting in one or more emergency oil pumps for furnishing the fluid for hydraulic operation of the governor of the main turbine and the lubrication of its bearings, and in the drawings the numeral 16 in each instance designates one of these pumps which is adapted to be directly driven by a small emergency steam turbine 17. Each of the turbines 17 is connected through a pipe 18 with a main steam supply pipe 19 which, as shown in Fig. 3, is provided with a shut off valve 20. The oil pumps 16 furnish both the hydraulic pressure fluid and the lubricant. For bringing the oil delivered by these pumps down to the lower lubricating pressure, the section 21 of the delivery pipe

5 piping from the pumps 16 which connects with the piping 15 receives its oil through a reducing valve 22 connected with the delivery pipe 23 of the pumps 16. A branch pipe 24 supplies the pressure fluid to the pipe 12. Passage of hydraulic fluid from either the pump 7 or the pump 8 to the pumps 16 while the pumps 7 or 8 are in operation is prevented by check valves 25 in the piping 23. Passage of hydraulic fluid from either of the pumps 16 to either 7 or 8 when either of the pumps 16 are in operation is prevented by check valves 26, one of these being in the piping 15 and the other being in the piping 12.

The subject of this invention is especially concerned with the control of the cut off valve 20. In the present instance this valve 20 is mounted in a closed position by connection of its slidably mounted stem 27 with a piston 28 slidably mounted in the bore of a cylinder 29 having a lower closed end 30 which connects through a port 31 and piping 32 having a three way valve 33 adapted to connect by a pipe 34 with the piping 12, 24 in one position of the valve and with a waste pipe 35 in the other position of said valve. The cylinder 29 has an end cap 36 forming a support for the housing 37 for the valve 20, this housing being carried by upright studs 38 mounted on the cap 36. The stem or rod member 27 for the valve 20 works through a suitable stuffing box 39. During normal operation of the turbine, when the pumps 7 and 8 are being driven thereby, the pressure of the hydraulic fluid is communicated to the space below the piston 28 through the piping 12, 24, 34, valve 33, and piping 32, and port 31, and the over all pressure on the piston 28 is such as to hold the valve 20 closed against the steam pressure in the supply line 19.

The valve 33 is provided with an exterior operating arm 40 which carries a weight 41 adjustably mounted thereon at its outer end. This weighted arm connects by a latch 42 pivotally mounted on the pin 43, carried by the arm 40, with a catch 44 carried by an evener bar 45. One end of the evener bar 45 is connected by a pin and slot connection 46 with the rod 47 of a piston 48 working in the bore 49 of a control cylinder 50 having an end cap 51 connected by a pipe 52 with the piping 15 and 21, so that pressure fluid from the lubricant system for the turbine may flow to the bore 49 to act against the piston and its return spring 52' so as to bring the piston to a stop position defined by the shoulder 53 in the cylinder 50 and under which conditions the evener bar 45 is in a latching position. The other end of the evener bar has

a pin and slot connection 54 with the rod 55 of a piston 56 operating in a bore 57 of a cylinder 58. The cylinder 58 has an end cap 59 connected with piping 60 that connects with the piping 12, 24, so that the normal pressure of the hydraulic governor operating fluid acting upon the piston 56 will urge it to a stop position against the shoulder 61 and also compress the return spring 62 interposed between the piston and a rear end cap 63. Under these conditions the evener bar 45 is in its position of equilibrium with the latch 42 engaging the catch 44. To facilitate this engagement the latch 42 is normally acted upon at its lower end by its leaf spring 64 and is limited in its latching movement by a stop 65. If for any reason the pressure in either the governor operating fluid supply or the lubricant supply for the main turbine 5 should drop below its normal predetermined operating pressure, then either the piston 48 or the piston 56 will under the action of its spring 52' or 62, respectively, move outwardly toward the cap 51 or 59, respectively, and thus cause an angular shifting of the evener bar 45 with its consequent release from the latch 42, so that the arm 40 then drops through the action of the weight 41 and turns the three way valve 33 to an open position in which the pipe 34 is shut off and the oil under piston 28 holding the valve 20 closed is free to drain through piping 32 and 35 to atmosphere, thus permitting the steam pressure acting on the valve 20 to immediately open the same and allow steam to flow through the supply pipe 19 to either of the turbines 17 whose throttle valve has been opened so as to start the drive of one of the pumps 16 which then continues to furnish its supply of pressure fluid for supplying the governor operating fluid and the lubricant to the main turbine until either of the pumps 7 or 8 that has gone out of commission has been repaired.

In each instance the numeral 66 designates a valve controlling the passage of hydraulic fluid from either the piping 15, 21 or 12, 24 to waste or drain.

I desire it to be understood that this invention is not to be limited to any particular form or arrangement of parts except in so far as such limitations are included in the claims.

What I claim as my invention is:

1. In power generating equipment having a main steam turbine and an auxiliary steam turbine, a pump for furnishing hydraulic governor operating fluid for said main turbine at a predetermined pressure, a pump for furnishing lubri-

cant to said main turbine at another pressure, means for driving said pumps from said main turbine, and an emergency hydraulic fluid pump driven by said auxiliary turbine, control mechanism for said auxiliary turbine comprising a valve controlling the supply of steam to said auxiliary turbine, and hydraulically controlled means dependent upon the proper supply of hydraulic fluid at said different pressures by the first and second named pumps respectively for controlling said steam valve.

2. In power generating equipment having a main steam turbine and an auxiliary steam turbine, a pump for furnishing hydraulic governor operating fluid for said main turbine at a predetermined pressure, a pump for furnishing lubricant fluid to said main turbine at another pressure, means for driving said pumps from said main turbine, and an emergency hydraulic fluid pump driven by said auxiliary turbine, control mechanism for said auxiliary turbine comprising a valve controlling the supply of steam to said auxiliary turbine, hydraulically operated means for exerting a closing pressure on said valve, and means normally equalized between the pressures of said pumps for the main turbine for relieving said closing pressure operable on the failure of either of said first named pumps to supply the main turbine with the proper amount of fluid.

3. In power generating equipment having a main steam turbine and an auxiliary steam turbine, a pump for furnishing hydraulic governor operating fluid for said main turbine, a pump for furnishing lubricant fluid to said main turbine, means for driving said pumps from said main turbine, and an emergency hydraulic fluid pump driven by said auxiliary turbine, control mechanism for said auxiliary turbine comprising a valve controlling the supply of steam to said auxiliary turbine, means operable by the hydraulic fluid from one of said pumps for holding said steam valve closed, and means for relieving the closing pressure upon said steam valve comprising a cut off and drain valve, gravity-actuated means for moving said last named valve to a drain position, latching means for normally holding said gravity-actuated means in an inoperative position including an evener bar and fluid pressure operated means for each end of said bar, one of said last named means operating in response to the pressure of the governor operating fluid and the other of said last named means operating in response to the pressure of the lubricant fluid.

FREDERICK L. DORNBROOK
